UNITED STATES PATENT OFFICE.

JOSEPHINE M. DILLMEIER, OF NEW YORK, N. Y.

CASSEROLE HOLDER.

Application filed December 9, 1920, Serial No. 429,368. Renewed January 12, 1923.

To all whom it may concern:

Be it known that I, JOSEPHINE M. DILLMEIER, of New York, in the county of New York and State of New York, have invented 5 certain new and useful Improvements in Casserole Holders; and I do hereby declare the following to be a full, clear, and exact description of the invention, such as will enable others skilled in the art to which 10 it appertains to make and use the same.

My present invention is an improvement upon the type of holder covered by Letters Patent No. 1,305,201 issued to me May 27, 1919, in that it contemplates novel means 15 for holding the radial bars in their channel plates.

Figure 1 is a plan showing the formations the holder can be made to assume. Figure 2 is a section on line 2—2, Figure 3, which latter is a detail in side elevation. Figures 20 4 to 7 are details.

As in the patent mentioned, the structure comprises a circular rigid base 1 having on its under face four channel plates 2 arranged at angles of 90 degrees. A bar 3 is movable in each of these channel plates. 25

According to my present improvements these bars 3 terminate at their outer extremities in upward extending right angular arms 4. These are attached to the lazy tongs side frame 5 by pins 6 passing through the adjacent middle hinge connection between 30 two of the series of levers constituting the frame.

The structure is equipped with four peripheral supporting feet 7. As shown these consist of bars bent back upon themselves to form flat bases 8 and having their upper ends forming handles 9 of appropriate ornamental design. The pins 6 pass through the overlapping portions of the bars and the latter are secured together by a rivet 10. The central base 1 may also be equipped 40 with a foot 12. Thus the levers of the lazy tongs frame may turn on pins 6 to vary the size and shape of the holder according as the bars 3 are moved in their channel plates.

I make provision for the bars being capable of ready manipulation and yet be secured as against accidental displacement. 50 As shown in Figures 4 to 7 each plate is formed throughout a portion of its length with a longitudinal slot 13. Its comple-

mentary bar 3 has a stud 14 projecting from its under face. The spindle portion of this stud is within the slot 13 and its outer head spans the slot and bears against the adjacent lower face of the channel plate. Thus an effective guide is provided as well as means for preventing the accidental separation of the parts and for limiting the range of adjustment of the bars. 55 60

To frictionally retard the movement of the bars I provide the channel plates with spring plates 15 on their under faces. The 65 springs are secured near one end as at 16 and they each carry a friction foot 17 projecting through a hole in the channel plate and into contact with bar 3. The tendency of these springs is to bear against the bars 70 sufficiently to allow of manual adjustment while preventing accidental displacement.

I claim as my invention:

1. A casserole holder comprising a central base, a flexible side frame, horizontally extensible bars radiating from said base and terminating at their outer extremities in upward extending right angular arms, supporting feet adjacent said arms comprising bars 75 bent back upon themselves to form flat bases 80 and having their upper ends forming handles, and pins passing through said side frame, said arms and said feet.

2. A casserole holder comprising a central base, a flexible side frame, channel plates on 85 said base each having a spring actuated friction foot, and a bar in each of said channel plates engaged by said friction foot, said bar being connected to said side frame.

3. A casserole holder comprising a central 90 base, a flexible side frame, channel plates on said base each having a longitudinal slot, a hole in advance of said slot, a spring plate secured to the under face of said channel plate having a friction foot projecting 95 through said hole, and a bar in each of said channel plates engaged by said friction foot and having a stud movable in said slot, said bars being connected to said side frame.

In testimony whereof I have signed this 100 specification.

JOSEPHINE M. DILLMEIER.
